UNITED STATES PATENT OFFICE.

WILLIAM BARNETT, OF PORTLAND, OREGON.

ADJUSTABLE SINK-BRACKET.

1,253,924.

Specification of Letters Patent. Patented Jan. 15, 1918.

Application filed September 7, 1916; Serial No. 118,880. Renewed November 26, 1917. Serial No. 204,133.

To all whom it may concern:

Be it known that I, WILLIAM BARNETT, a citizen of the United States, residing at Portland, in the county of Multnomah and 5 State of Oregon, have invented certain new and useful Improvements in Adjustable Sink-Brackets, of which the following is a specification.

This invention relates to an adjustable 10 sink bracket and the primary object is to provide a bracket adapted to be secured to the wall and provided with adjustable supporting arms which may be regulated for supporting various standard sizes of sinks.

Another object of the invention resides in 15 the provision of a bracket of this character having adjustable extension arms held in place by the weight of the sink in adjusted position without the use of screws or other 20 fastening elements.

A still further object of the invention is the provision of a bracket which may be converted into a shelf bracket for supporting shelves of various widths.

25 A further object of this invention is the provision of an adjustable sink bracket which consists of comparatively few parts and is simple in construction, but durable and well adapted to withstand the rough 30 usage to which devices of this character are ordinarily subjected.

For a full description of the invention and the advantages and merits thereof, reference 35 is to be had to the following description and the accompanying drawings, wherein is illustrated the preferred form of my invention, in which;

Figure 1 is a side elevation showing the invention in applied position.

40 Fig. 2 is a top edge view.

Fig. 3 is a section on the line 3-3 of Fig. 1.

Fig. 4 is an elevation of the bracket as it is used for supporting a shelf.

45 Fig. 5 is a detail perspective view.

Referring to the drawing, wherein is illustrated the preferred form of my invention, and in which like numerals of reference indicate corresponding parts throughout the 50

several views, the stationary supporting arm 1 is formed from a strip of metal and has one end twisted and bent at right angles to provide the fastening flange 2 having apertures for receiving the fastening screws 3 which are driven into the wall A for supporting the stationary supporting arm 1.

The lower edge 4 of the supporting arm 1 is provided with a plurality of struck-out portions 5 forming stop lugs spaced apart at pre-determined intervals. The free end of 60 the supporting arm 1 is tapered toward its end and twisted to provide the retaining notch 6 and the terminal of the twisted portion is extended upwardly from the notch for providing a retaining finger 7. 65

An adjustable supporting arm 8 is formed from a strip of metal of the same material from which the stationary supporting arm 1 is formed, and its inner end is tapered and twisted in the same manner as the outer end 70 of the supporting arm 1, thereby providing a notch 9 and a retaining finger 10. The opposite end of the adjustable arm 8 is bent to provide the stop arm 11. A pivot pin 12 is carried by the stationary supporting arm, 75 adjacent the free end thereof, and receives one end of a truss bar 13 twisted at its opposite end to provide the retaining flange 14 having openings for the reception of the fastening screws 15 which are driven into the 80 wall A.

The stop lugs on the stationary supporting arm 1 are spaced apart at a pre-determined distance and are adapted to contact with the edge of the retaining finger 10 for 85 preventing the adjustable supporting arm from moving on the stationary supporting arm when the sink B, shown by dotted lines in Fig. 1, is in position. The stop lugs are disposed at a distance to accommodate the 90 various sizes of sinks and it will be observed that the adjustable supporting arm may be raised out of the notch 6 and the notch 9 may be pulled out of engagement with the stationary supporting arm 1. It then may 95 be moved forwardly and the retaining finger 10 placed in engagement with the edge of one of the other stop lugs 5. Thus the width of a sink of a larger size may be accommodated. 100

The flange 1 which extends around the edge of the standard sinks, rests upon the top edges of the stationary arm and the adjustable supporting arm thereby providing a convenient and efficient supporting 105 bracket for the sink.

As shown by Fig. 4 of the drawing the same construction is employed for a shelf bracket. The only difference being the free end of the adjustable supporting arm 8' 110 which is provided with the upturned stop bar 16 instead of the horizontally disposed

member 11. The shelf C is then mounted upon the stationary supporting arm and the adjustable supporting arm and the front edge of the shelf contacts with the member 5 16 thereby preventing the displacement of the shelf.

From the foregoing it will be observed that a very simple and durable adjustable sink bracket has been provided, the details 10 of which embody the preferred form. I desire it to be understood however, that slight changes in the minor details of construction may be made without departing from the spirit of the invention or the scope 15 of the claims hereunto appended.

I claim:

1. A bracket of the character described comprising a stationary supporting arm and an adjustable supporting arm, one of said 20 arms having stop lugs formed of struck-out portions in the lower marginal edge of the arm, the corresponding arm having means formed at its end for coöperating with the said struck-out portions to permit 25 the longitudinal adjustment of the said adjustable supporting arm with respect to the stationary arm.

2. A bracket of the character described comprising a stationary supporting arm and 30 an adjustable supporting arm, the proximate ends of each of said arms being tapered and twisted to provide notches for the reception of the corresponding arm, one of said arms having stop lugs formed of 35 struck-out portions in one edge of a width greater than the width of the said notch in the adjacent arm.

3. A bracket of the character described comprising a stationary supporting arm and 40 an adjustable supporting arm, the proximate ends of each of said arms being tapered and twisted to provide notches for the reception of the corresponding arm, one of said arms having stop lugs formed of 45 struck-out portions in one edge of a width

greater than the width of the said notch in the adjacent arm, and retaining fingers formed at the terminal of each arm and extending upwardly from the adjacent notch.

4. A bracket of the character described comprising a stationary supporting arm and an adjustable supporting arm, the proximate ends of each of said arms being tapered and twisted to provide notches for the reception of the corresponding arm, one of 50 said arms having stop lugs formed of struck-out portions in one edge of a width greater than the width of the said notch in the adjacent arm, retaining fingers formed at the terminal of each arm and extending upwardly from the adjacent notch, the terminal of the said stationary supporting arm being twisted and bent at right angles to provide a retaining flange, and a stop arm formed on the free end of the adjustable 55 supporting arm.

5. A bracket comprising a pair of supporting arms, one being stationary and the other adjustable, the stationary arm having a fastening flange for disposing the arm 70 edgewise, the lower edge of the arm having struck-out portions providing stop lugs disposed at equally spaced intervals, the adjustable supporting arm being tapered at one end and bent to provide a notch for receiving the said lower edge of the stationary supporting arm and terminating in a retaining finger embracing the said stationary arm, the said stationary supporting arm also being tapered and provided with a 75 notch at its end and having its terminal bent to provide a retaining finger for embracing the said adjustable arm.

In testimony whereof I affix my signature in presence of two witnesses.

WILLIAM BARNETT.
